UNITED STATES PATENT OFFICE.

SAMUEL F. SHAFER, OF TACOMA, WASHINGTON.

FURNACE.

Application filed December 8, 1919. Serial No. 343,277.

To all whom it may concern:

Be it known that I, SAMUEL F. SHAFER, a citizen of the United States, residing at Tacoma, in the county of Pierce and State of Washington, have invented a new and useful Furnace, of which the following is a specification.

By way of explanation it may be stated that, in a furnace, as ordinarily constructed, the air to be heated, on the one hand, and the products of combustion, on the other hand, move upwardly together. As a consequence, the air can be no hotter than the products of combustion, at the time the products of combustion enter the stack. The foregoing being understood, one object of the invention is to provide a furnace so constructed that the air to be heated will move upwardly, the products of combustion moving downwardly, or stated differently, the air may move to the right when the products of combustion move to the left.

In any event, the air comes under the influence of the products of combustion, at the time that the products are at the highest temperature, and just before the air is permitted to pass from the furnace.

It is within the province of the disclosure to improve generally and to enhance the utility of devices of that type to which the invention appertains.

In the drawings:—

Figure 1 shows in longitudinal section, a hot air furnace constructed in accordance with the invention; Figure 2 is a cross section on the line 2—2 of Figure 1, distant parts being omitted; Figure 3 is a cross section on the line 3—3 of Figure 1; Figure 4 is a cross section on the line 4—4 of Figure 1; and Figure 5 is a fragmental horizontal section illustrating the structure delineated in Figure 4.

Referring to Figures 1, 2 and 3, the numeral 1 denotes a casing embodying a front wall 21 and a rear wall 31. Adjacent to its front, the casing 1 carries a hood 2 from which lead pipes 3 adapted to convey the heated air to the points of application. A wall 4 extends entirely across the casing 1. A wall 5 extends part way across the casing, and is located in front of the wall 4. Sides 8 extend between the front wall 21 and the wall 4. A top plate 6 connects the wall 21 with the wall 5 and the wall 4. The construction is such that a combustion chamber is defined, the sides 8 of the combustion

chamber being spaced from the sides of the casing 1. The furnace embodies an ash pit 9, and from the ash pit, a passage 10 leads upwardly, this passage being bounded by 60 the walls 4 and 5 and by the rear portions of the sides 8. The furnace includes a fire pot 12 having a grate 14. The stoke door is denoted at 16, the ash door being shown at 15. An air flue 11 extends downwardly between 65 the combustion chamber and the side wall of the casing 1, one end 70 of the air flue opening into the combustion chamber through the top 6, and the other end 71 of the air flue communicating with the atmosphere 70 through the said side wall of the casing. The front wall 21 of the casing is bulged outwardly as shown at 201, adjacent to the fire pot 12, the space thus defined communicating with the spaces which exist between 75 the sides 8 of the combustion chamber and the sides of the casing 1.

A baffle plate 17 extends across the casing 1 from side to side and projects rearwardly from the wall or partition 4. A 80 baffle plate 18 is located below the baffle plate 17 and projects forwardly from the rear wall 31 of the casing.

A box-like header 19 is carried by the rear wall 31 of the casing and extends transversely thereof, the header 19 being supplied with clean out closures 20 giving access not only to the header but, as well, to pipes 25 hereinafter mentioned. A pipe 28 leads from the top of the header 19 to a stack 29. 90 The rear wall 31 of the casing terminates adjacent to the bottom of the header 19, so that, at the lower end of the casing and at the back thereof, there exists an air inlet opening 22.

Pipes 23 extend between the partition 4 and the rear wall 31, the pipes communicating at their forward ends with the passage 10. The rear ends of the pipes 23 are stopped by clean out closures 33. The ends 100 of pipes 24, located below the pipes 23, are carried by the partition 4 and the rear wall 31. Pipes 25, located below the pipes 24 are mounted at their forward ends in the partition 4, the rear ends of the pipes 25 being carried by the wall 31 and communicating with the header 19. The forward ends of the pipes 25 and 24 are controlled by dampers 34, the rear ends of the pipes 24 being stopped by clean out closures 33 of the sort 110 hereinbefore mentioned in connection with the pipes 23. The pipes 23 and 24 are

united adjacent their rear ends by connections 27, connections 26 uniting the pipes 24 and 25 adjacent to their forward ends. The baffle plate 17 lies between the pipes 23 and 5 the pipes 24, the baffle plate 18 lying between the pipes 24 and the pipes 25. For convenience, the parts 23, 27, 24, 26 and 25 may be alluded to as a sinuous flue forming a communication between the upper portion 10 of the passage 10 and the header 19. From the center pipe 23, a branch 30 leads to the stack 29, the branch 30 containing a damper 32. From the branch 30, elbows 40 lead to the side pipes 23. The wall 5 is provided 15 with an opening 36, communicating with the passage 10 and controlled by a damper 35.

Let it be supposed that the dampers 35, 34 and 32 are closed. Then the operation of the structure is as follows:

20 Air enters the combustion chamber by way of the air flue 11 air being admitted into the flue at the lower end 71 thereof, and being discharged into the combustion chamber at the upper end 70 of the flue. The air 25 thus admitted passes downwardly through the fire pot 12, the products of combustion passing downwardly into the ash pit 9 and moving upwardly through the passage 10. The products then enter the pipes 23 and 30 traverse the parts 24, 26 and 25, the products entering the header 19 and passing into the stack 29 by way of the pipe 28. Air enters the casing 1 through the opening 22 in the rear lower portion of the casing. The 35 air moves upwardly around the forward end of the lower baffle 18, around the rear end of the upper baffle 17 and, ultimately, enters the hood 2 and leaves by way of the pipes 3 to the points of use. Obviously, the 40 air moving as described, comes in contact with the sinuous flues formed by the parts 23—27—24—26—25 and is heated thereby. Just before the air enters the hood 2, the 45 air comes into contact with the hottest parts of the pipe 23, owing to the fact that there is a down draft of the products of combustion, and an up draft of the fresh air. If desired, the dampers 32 and 35 may be opened, and then there will be a check draft 50 from the combustion chamber 8 above the fire pot 12 to the passage 10, through the pipes 23 into the stack 29, by way of the elbows 40 and the branch 30. The lower damper 34 may be opened, thereby creating 55 a draft from the passage 10 to the header 19, the pipes 28 and the stack 29, through the pipes 25 only. The lowermost damper may be closed, and the uppermost dampers at the inner ends of the pipes 24 may be 60 opened, whereupon there will be a draft from the passage 10 through the pipes 24, the connections 26 and the pipes 25. The operator, therefore, has under his control, 65 a means whereby the regulated or adjusted portions of the sinuous flue 23—27—24

26—25 may be subjected to the products of combustion, the heating area being regulated accordingly.

Having thus described the invention, what is claimed is:

1. In a device of the class described, a casing embodying a front wall, a rear wall, sides and a top, the lower rear portion of the casing having an inlet for cold air, and the upper front portion of the casing having an outlet for heated air; a transverse wall extended entirely across the casing from side to side and spaced at its upper edge from the top of the casing; a combustion chamber in the casing and located in front of the transverse wall, the sides of the chamber being spaced from the sides of the casing, the chamber terminating short of the bottom of the casing, and being spaced from the transverse wall to form a passage 75 communicating with the space below the combustion chamber and closed at its top; an air flue opening at its upper end into the combustion chamber and extended 80 downwardly between one side of the casing and the corresponding side of the chamber, the flue communicating at its lower end with the atmosphere; a stack at the rear of the casing; a header extended across the rear end of the casing; a communication 85 between the header and the stack; sinuous flues opening at their lower rear ends into the header and opening at their upper forward ends into said passage, the intermediate portions of the flues communicating 90 with said passage; dampers controlling the points of communication between the sinuous flues and the passage; a damper controlling the flow of the products of combustion 95 from the combustion chamber directly 100 into the passage; a pipe connecting the upper portions of the sinuous flues with the stack; and a damper in the pipe.

2. In a device of the class described, a 110 casing embodying a front wall, a rear wall, sides and a top, the lower rear portion of the casing having an inlet for cold air, and the upper front portion of the casing having an outlet for heated air; a transverse wall extended entirely across the casing from side to side and spaced at its upper edge from the top of the casing; a combustion chamber in the casing and located in front of the transverse wall, the sides of the chamber being spaced from the sides of the casing, the chamber terminating short of the bottom of the casing, and being spaced from the transverse wall to form a 115 passage communicating with the space below the combustion chamber and closed at its top; an air flue opening at its upper end into the combustion chamber and extended 120 downwardly between one side of the casing and the corresponding side of the chamber, the air flue communicating at its lower end 125

with the atmosphere; a stack at the rear of the casing; a sinuous flue in the casing, the flue communicating at its upper forward end with said passage; means for establishing communication between the lower rear end of the flue and the stack; damper means for placing the intermediate portion of the flue in communication with said passage, at the will of an operator; and damper means for placing the combustion chamber

in direct communication with said passage, at the will of an operator.

In testimony that I claim the foregoing as my own, I have hereto affixed my signature in the presence of two witnesses.
